UNITED STATES PATENT OFFICE.

JOHN R. WARREN, OF GRAND RAPIDS, MICHIGAN, ASSIGNOR TO THE PISTON RING COMPANY, OF MUSKEGON, MICHIGAN, A CORPORATION OF MICHIGAN.

PISTON.

Application filed November 18, 1921. Serial No. 516,016.

To all whom it may concern:

Be it known that I, JOHN R. WARREN, a citizen of the United States, residing at Grand Rapids, in the county of Kent and State of Michigan, have invented new and useful Improvements in Pistons, of which the following is a specification.

The present invention relates to pistons; and its object is to provide a piston having a body member and a surrounding sleeve member, which members may be readily connected and in such manner that leakage between them will be prevented.

This and any other objects hereinafter appearing are attained by, and the invention is preferably embodied in, the structure hereinafter particularly described and illustrated by the accompanying drawing, in which:—

20 Figure 1 is a top plan view of a piston; Figure 2 is a side view thereof;

Figure 3 is an axial sectional view of the same taken on a plane corresponding to line 3—3 of Figures 2, 4 and 5, and showing a portion of the cylinder containing the piston;

Figure 4 is a bottom plan view of the piston, the piston rod being omitted;

Figure 5 is a transverse sectional view 30 of the body member of the piston taken on a plane corresponding to line 5—5 of Figure 3;

Figure 6 is a view similar to Figure 2, but showing a modified construction;

35 Figure 7 is a sectional view of a fragment of the same taken on a plane corresponding to line 7—7 of Figure 6; and

Figure 8 is an axial sectional view of a portion of the piston taken on the same 40 plane as that on which Figure 3 is taken, but showing a modified construction.

In the embodiment of the invention chosen for illustration by the drawings and for detailed description in the body of this specification, a piston reciprocating in a cylinder 1 of an internal-combustion engine is shown. This piston comprises a body member 2 carrying the piston pin 3 on which is rockably mounted the piston rod indicated at 4. The piston comprises also the sleeve member 5 surrounding the body member and, being resiliently expansive, bearing on the interior of the cylinder. The body member 2 has at one end an outwardly extending continuous flange 6 against which

the corresponding end 7 of the sleeve member abuttingly contacts tightly. The sleeve member is held in such contact with this flange by the mutual engagement of the radially extending portions 8 of the body member and 9 of the sleeve member. As seen in Figures 3 and 4, these portions 8 are spaced apart angularly and the portions 9 are similarly spaced, so that in assembling the two members 2 and 5, the portions 8 are passed between the portions 9 as the members 2 and 5 are interrelatively moved in their axial direction, whereupon these members are interrelatively turned about their axes, so that said portions are moved 70 to their mutually engaging position seen in Figures 3 and 4. These radially extending portions, instead of being divided into the spaced apart sections seen in Figures 3 and 4, may however be fashioned in continuous 75 annular form as seen at 8¹ and 9¹ in Figure 8, and their surfaces 10, 11 may be inclined as shown, so that the sleeve member 5 may be expanded to permit its assembly with the body member 2 by being 80 pushed over its lower end, whereupon the sleeve member contracting will cause the portions 8¹ and 9¹ to lockingly engage.

The sleeve member is resiliently expandable and contractible, having a longitudinally disposed slit 12, a portion 13 thereof extending in the transverse direction of the sleeve member. In this portion 13 of the slit 12 the parts of the sleeve member tightly contact each other, but slidably, so that 90 leakage from that portion of the slit 12 which is at one side of the portion 13 to that portion of said slit which is at the opposite side of the portion 13 is prevented, said portion 13 registering in the assembled 95 position of the members 2 and 5 with the body member's flange 14 as seen in Figure 3; or, a slit 15 may be provided extending across the slit 12 and containing a dam plate 16 closely fitting but slidable therein 100 to permit the transverse expansion and contraction of the sleeve member, as seen in Figures 6 and 7. In order to maintain the end 7 of the sleeve member in tight contact with the body member's flange 6, to prevent 105 leakage between said members, the sleeve member is longitudinally contractible and expandable resiliently. To this end, the sleeve member has a series of transversely extending slits 18 disposed end to end, and 110

a second series of like slits 19 similarly disposed, the slits of one series being staggered relatively to those of the other series, as seen in Figure 2. A cotter pin 20 holds 5 the members 2 and 5 against interrelative turning movement.

The invention being intended to be pointed out in the claims, is not to be limited to or by details of construction of the 10 particular embodiment thereof illustrated by the drawings or hereinbefore described.

I claim:

1. In a piston; a body member carrying the piston rod and having a radially extending flange and a radially extending portion; a diametrically expandable and contractible sleeve member surrounding the body member and having a radially extending portion adapted to engage the body 20 member's said portion to press in the piston's longitudinal direction an end of the sleeve member in tight contact with said flange.
2. In a piston; a body member carrying the piston rod and having a radially extending flange and a radially extending portion; a diametrically expandable and contractible sleeve member surrounding the body member and having a radially extending portion adapted to engage the body 30 member's said portion to hold an end of the sleeve member in tight contact with said flange; at least one of said radially extending portions having an inclined surface.
3. In a piston; a body member carrying the piston rod and having a radially extending flange and radially extending portions angularly spaced apart; a diametrically expandable and contractible sleeve 40 member surrounding the body member and the ends of the piston rod and having radially extending portions angularly spaced apart and adapted to pass between the body member's said portions and to engage the same by the interrelative turning movement of said members about their longitudinal axis to hold an end of the sleeve member in tight contact with said flange.
4. In a piston; a body member carrying the piston rod and having a radially extending flange and a radially extending portion; a longitudinally-split sleeve member 50 surrounding the body member and the ends of the piston rod and having a radially extending portion adapted to engage the body member's said portion to hold an

end of the sleeve member in tight contact with said flange.

5. In a piston; a body member carrying the piston rod and having a radially extending flange and a radially extending portion; a diametrically and longitudinally expandable and contractible resilient sleeve member surrounding the body member and having a radially extending portion adapted 60 to engage the body member's said portion to press an end of the longitudinally compressed sleeve member in tight contact with said flange.

6. In a piston; a body member carrying the piston rod and having a radially extending flange and a radially extending portion; a diametrically and longitudinally expandable and contractible resilient sleeve member surrounding the body member and 70 having a series of transversely extending slits disposed end to end and a second series of transversely extending slits disposed end to end, the slits of one series being staggered relatively to those of the other series, the sleeve member having also a radially extending portion adapted to engage the body member's said portion to hold an end of the longitudinally compressed sleeve member in 75 tight contact with said flange.

7. In a piston; a body member carrying the piston rod and having a radially extending flange and a radially extending portion; a sleeve member surrounding the body member and having a longitudinally disposed slit and a second slit extending thereacross having a dam plate closely fitting but slidable therein to prevent leakage between the portions of the first mentioned slit which are on the opposite sides of said 90 plate, the sleeve member having also radially extending portion adapted to engage the body member's said portion to hold an end of the sleeve member in tight contact with said flange.

8. In a piston; a body member carrying the piston rod and having a radially extending flange; a diametrically and longitudinally expandable and contractible resilient sleeve member surrounding the body member; means for holding an end of the longitudinally compressed sleeve member in tight contact with said flange.

In testimony whereof I have hereunto set my hand at Grand Rapids, Michigan, 110 this 2nd day of November, 1921.

JOHN R. WARREN.
